Term of patent 14 years

(Cl. D64—11)

To all whom it may concern:

Be it known that I, Giuseppe Beccio, a citizen of Italy and residing at Milano, Italy, have invented a new, original, and ornamental Design for a Typewriter Frame, of which the following is a specification, reference being had to the accompanying drawing, forming part thereof.

Fig. 1 is a perspective view of a typewriter frame, showing my new design, the broken line showings being for illustrative purposes only; and

Fig. 2 is an exploded perspective view of the same.

I claim:

The ornamental design for a typewriter frame, substantially as shown and described.

GIUSEPPE BECCIO.
